UNITED STATES PATENT OFFICE

2,120,047

CAN COVER AND FASTENING MEANS
THEREFORHenry P. Turner, Chicago, Ill.; Drovers Trust &
Sav. Bank executor of said Henry P. Turner,
deceased

Application May 16, 1935, Serial No. 21,817

12 Claims. (Cl. 220—57)

The present invention relates to covers and fastening means therefor and particularly to a can cover which is entirely removable from the can although not necessarily so, and to a fastening means which holds the can cover in place firmly in order to efficiently seal the contents of the can when the cover is in place. This invention is particularly designed for use in the home canning of food stuffs and the like and contemplates the use of an open-mouthed can to which my invention is applied. The cover and fastening means therefor are quickly and easily applied to cans in which food has previously been canned in a factory and which has been opened by one of the numerous modern can openers which open such a can and leave a smooth rim portion on the inside rim of the can. Such can openers usually turn down the peripheral portion of the cover which remains after cutting out the central portion thereof and press the same against the inner wall of the can thus permitting the can to be filled again with food stuffs and sealed.

One object of this invention is to provide a simple can cover fastening means which may be quickly and efficiently applied to a cover having certain features which cooperate with the fastening means to lock the cover in place on a can.

Another object of this invention is to provide a simple two part fastening means of the character described which may be made in sizes to fit standard sized cans.

Another object of this invention is to provide a cover and fastening means therefor which will enable one to fill the can with the product which is to be preserved, then after sealing the can by means of the cover and fastening means, permit the escape of steam during the cooking of the contents thereof and later effectively prevent the entrance of air into the can when the cooking has ceased and the steam has condensed to create a vacuum in the can.

Another object of this invention is to provide a simple fastening means having portions engaging standard portions on the can which, with the fastening means, create the pressure necessary to firmly hold the cover in place. In carrying out this part of the invention the fastening means preferably engages the outwardly and downwardly turned outer rim portion of the can at the upper edge thereof as will be described more fully hereinafter.

Another object of this invention is to provide a sealing means of the character described which

is automatically locked in place against accidental displacement after the parts of the fastening means have been moved to their operative positions.

Another object of this invention is to provide means for determining when the relatively movable parts have reached their intended operative positions and for automatically stopping their relative movement at that position.

Another object of this invention is in the provision of a novel form of gasket which may be utilized over and over again in a manner which will be more fully explained later.

Another object of this invention is to provide a fastening means for holding a cover removably on a can and be so constructed as to permit other cans to be stacked thereon.

Other objects of this invention will appear hereinafter as the description thereof proceeds, the novel features, arrangements and combinations being clearly set forth in the specification and the claims thereunto appended.

In the drawing:

Fig. 1 is a top plan view of a device embodying my invention.

Fig. 2 is a cross-section taken along the line 2—2 of Fig. 1.

Fig. 3 is a side elevation of the fastening means shown in Figs. 1 and 2 and looking at the same from the left as viewed in Fig. 2.

Fig. 4 is a cross section taken along the line 4—4 of Fig. 1, and

Fig. 5 shows a modification of my invention in cross-section.

In Fig. 2 I have shown a can of the usual type used for canning vegetables and the like which are canned at the factory and sold in the stores to the consumer. Such cans have a peripheral cylindrical wall 10 to which a bottom 11 is secured with an over-lap seam 12 such as shown in Fig. 2. The top of the can is similarly secured by an over-lap seam 13 to the upper peripheral edge of the wall 10 of the can. When the central portion of the can cover is cut out by a can opener by certain types of can openers now on the market, the remaining peripheral portion 14 of the top inside the wall of the can is turned downwardly against the inside of the wall 10 as is clearly illustrated in Fig. 2, thus leaving a smooth inner surface 50 which will not injure one using the can and which will permit the ready insertion of a cover which may closely fit within this turned down peripheral portion 14. The over-lap seam forms a bead around the outer surface of the can at 55

the top thereof and this bead projects outwardly from the side of the can and provides a lower abutment shoulder 15 which I utilize in the present instance in a manner to be described presently.

In carrying out my invention I employ a cover 16 having a central raised portion 17 which is preferably flat but which may be convex or concave as desired. The central portion 17 is preferably surrounded by an outwardly and downwardly inclined cam portion 18 which extends to the upwardly extending vertical contiguous wall 19 which has a laterally extending horizontal portion 20 with a peripheral flange 21 thereon extending downwardly as is clearly illustrated in Fig. 2. The vertical wall 19, laterally extending portion 20 and the downwardly extending flange 21 form a downwardly facing annular recess in which is arranged a ring-like gasket 22 of rubber or the like. This gasket is preferably square in cross section so that after the same has been used it may be twisted throughout its length to present different surfaces in a vertical and horizontal direction. In Fig. 2 this gasket is shown compressed in a vertical direction due to the clamping pressure on the cover, but when not compressed the gasket would be square in cross-section. It will be noted that the underside of the gasket may become deformed after continued contact with the rim of the can which is much sharper than illustrated in the drawing, thus making this surface unsuited for sealing purposes. However, the other three surfaces on the gasket still will be in good condition and if these are presented to the upper edge of the can by twisting the gasket to present these surfaces they will effect a good seal and the gasket can be used longer than would otherwise be possible. Of course, the gasket can be shaped otherwise than illustrated and described, and the recess formed in the outer peripheral edge of the cover to receive the gasket would then be shaped more or less to conform with the shape of the gasket being used.

It will be noted that there is a slight clearance between the vertical wall 19 on the can cover and the downwardly turned peripheral portion 14 of the original cover for the can. This permits steam to escape from the can when the same is generated in the can during the cooking process, the cover acting as a safety valve.

I will now proceed to describe the fastening means which, in the form of the invention illustrated in Figs. 1 to 4, comprises a flat metal member 23 and an arm 24 which are pivoted to each other at 25 by a rivet or the like to permit angular movement relative to each other. The member 23 is provided at its outer extremities with downwardly extending portions 26 terminating in inwardly extending flanges or claws 27, the extreme inner ends of which are curved preferably to the same curvature as the outer portion of the can to which the cover and fastening device is to be applied. Satisfactory results can be obtained by having the inner ends of these claws perfectly straight but it is preferred that the same be made as described and shown in the drawing.

The arm 24 has a downwardly extending cam contacting portion 28 and is provided at its free outer extremity with a downwardly extending portion 29 terminating in an inwardly extending flange or claw 30, the inner edge 31 of which

is at a slight angle to the tangent of the can when the member and arm are in their full line positions shown in Fig. 1 and for a purpose to be described presently. Again it is not necessary that this edge be shaped as a cam but may be made to extend in the direction of the tangent or be curved, and still give satisfactory results.

The fastening means is applied in the following manner. The inwardly extending flanges or claws 27 are placed under the abutment shoulder 15 and against the outside wall 16 so as to prevent upward movement of the member 23, the arm 24 being in the dotted line position shown in Fig. 1 while this is being done. Downward pressure is then placed on the upper side of the arm 24 while one hand holds the bar 23 in place and while this pressure is exerted on the arm 24 the same is moved in a counterclockwise direction into the full line position shown in Fig. 1. The cam edge 31 is moved in a manner to engage the side of the can wall 16, below the abutment shoulder 15 and tensions the arm 24 in a longitudinal direction as it approaches the full line position. In the full line position, the claw 30 is under the abutment shoulder 15 as are the claws 27 and the result is that upward movement of the fastening means is prevented. During the movement of the arm 24 in the counterclockwise direction mentioned the cam contacting portion 28 on the arm rides up along the cam portion 18 of the cover on to the central flat portion 17 thereof, thus tending to exert a transverse vertical stress on the arm sufficient to hold the cover in place, it being understood that when the arm is in the dotted line position shown in Fig. 1 that the cam portion 28 lies within the recess surrounding the central portion and is below the level of the central portion 17 whereby a transverse stress is set up in the arm 24 as the cam portion 28 moves up on to the central portion 17 of the cover.

In order to limit the counterclockwise movement of the arm 24 and determine its operative position I form a slot 32 in the member 23 as will be noted in Fig. 1 and on the opposite sides of this slot I deform the portions of the arm oppositely in a vertical direction. This deformation is shown most clearly in Fig. 4 and in Fig. 1. The portion to the right of slot in Fig. 4 and above in Fig. 1 is turned downwardly as at 33, whereas the portion on the other side of the slot is turned upwardly as at 34.

The purpose of so forming the portions of opposite sides of the slot 32, is two-fold. The downwardly extending portion 33 acts as a stop which engages the side of the arm 24 when it reaches the full line position in Fig. 1, thereby determining the operative position thereof. The forming of the portion 34 as described and as shown in Fig. 4 leaves a recess in the underside of the member 23 into which a detent 35 is formed on the upper side of the arm 24 rides, to thereby hold the arm 24 in its operative position against accidental movement in a clockwise direction. This detent 35 is struck up out of the edge of the arm 24 and when the arm 24 leaves its operative position it will be noted that this detent is swung clear of the member 23 so as not to frictionally retard the angular movement of the arm 24, whereby a free and easy movement of the bar is obtained except close to the operative position thereof. Of course, this detent and stop could be formed otherwise than as shown but I have found that the con-

struction illustrated forms a very simple construction which lessens the cost of manufacture of the device and efficiently performs the intended functions therefor.

- 5 It will be obvious that a dome shaped central portion for the cover or even a cover having a central concave portion may be suitable for use with the fastening means shown in this application and therefore I do not wish to limit myself to the construction shown except as hereinafter set forth in the claims. Note also that in the construction shown the portions 18 act to brace the central portion 17 and prevent the downward movement thereof, whereby the 10 clamping action does not materially move the central portion of the cover in a downward direction and thus lose the effectiveness of the fastening means.

In Fig. 5 I have shown a modified arrangement of my invention in which the cover is provided with a central concave portion 36 in which the somewhat spherical cam engaging portion 37 formed on the arm 38 rests when the arm is in operative position, the cover having a cam portion 39 similar to 18 in Figs. 1 to 4 inclusive. This concave portion does not need to be very deep or very large in diameter. Even a slight concave or depressed portion would be sufficient. With this arrangement the cam engaging portion 37 and concave portion 36 act as detent means and this makes it unnecessary to provide separate detent means to hold the arm 38 in operative position as at 34-35 in Figs. 1 to 4, inclusive.

35 I do not wish to limit my invention to cans of the nature which I have described as it is obvious that my device can be used with other cans or receptacles which are provided with an abutment surface or surfaces (not necessarily a continuous abutment) about the peripheral surface thereof, and facing in a downward direction. However, it would be more practicable probably to form a continuous downwardly facing abutment surface on the exterior side thereof for use 45 with a device such as set forth herein.

It is to be noted that the upper surfaces of the member 23 and arm 24, near the peripheral edge of the cover, are substantially in the same plane and are preferably so made so that other cans 50 may rest on these members in an upright position, thus enabling the housewife to store them on her shelves the same as ordinary canned food purchased at a store. While not necessary, it is also possible to form the outer ends of the member 23 and arm 24 with arcuate depressions at a 55 position in substantially vertical alignment with the side walls of the can so that the lower edge of another can formed as in Fig. 2 may rest in these grooves to prevent lateral sliding movement of the same when placed upon a can sealed as described herein.

Obviously those skilled in the art to which this invention pertains may make various changes in the arrangement and construction of the parts herein shown without departing from the scope of this invention, and therefore I do not wish to limit myself except as is hereinafter set forth in the claims hereunto appended.

Having thus fully described my invention what 70 I claim and desire to secure by Letters Patent of the United States is:

- 75 1. A fastening device of the class described comprising a flat member adapted to extend over the cover to be held in place, having downwardly and inwardly extending claws to act as retaining

means, and an arm pivoted substantially centrally of said member, a downwardly and inwardly extending claw on the free end of said arm to form with the other downwardly and inwardly extending claws on said member, a means for retaining said device in place on a can, said arm having a cover engaging portion for holding said cover in place under pressure when the said device is in operative position on a can provided with a cover, said member having a slit in the edge thereof, which slit lies adjacent one edge of said arm when said arm is in operative relation with said member, said member having a portion adjacent said slit extending into a position to engage the side of said arm to limit the pivotal movement 15 away from operative position while permitting pivotal movement thereof in the opposite direction.

2. A fastening device of the class described comprising a flat member adapted to extend over the cover to be held in place, having downwardly and inwardly extending claws to act as retaining means, an arm pivoted substantially centrally of said member, a downwardly and inwardly extending claw on the free end of said arm to form with the other downwardly and inwardly extending claws on said member, a means for retaining said device in place on a can, said arm having a cover engaging portion for holding said cover in place under pressure when the said device is in operative position on a can provided with a cover, said member having a slit in the edge thereof, which slit lies adjacent one edge of said arm when said arm is in operative relation with said member, said member having a portion adjacent said slit 30 extending into a position to engage the side of said arm to limit the pivotal movement away from operative position while permitting pivotal movement thereof in the opposite direction, said member having a portion on the other side of said slit deformed in a direction away from said arm to provide a recess, and a detent formed on said arm adapted to engage within said recess when said arm is in operative position to hold said arm against accidental displacement from its operative 35 position.

3. A fastening device of the class described comprising a flat member adapted to extend over the cover to be held in place, having downwardly and inwardly extending claws to act as retaining means, an arm pivoted substantially centrally of said member, a downwardly and inwardly extending claw on the free end of said arm to form with the other downwardly and inwardly extending claws on said member, a means for retaining said device in place on a can, said arm having a cover engaging portion for holding said cover in place under pressure when the said device is in operative position on a can provided with a cover, said member having a slit in the edge 60 thereof, which slit lies adjacent one edge of said arm when said arm is in operative relation with said member, said member having a portion adjacent said slit extending into a position to engage the side of said arm to limit the pivotal movement away from operative position while permitting pivotal movement thereof in the opposite direction, said member having a portion on the other side of said slit deformed in a direction away from said arm to provide a recess, and a 65 detent formed on said arm adapted to engage within said recess when said arm is in operative position to hold said arm against accidental displacement from its operative position, said detent being so arranged on said arm as to swing clear 70

of said member after a slight pivotal movement of said arm in its permitted direction of movement about its pivot.

4. A device as set forth in claim 2 in which the upper surfaces of said arm and member are formed with portions near the extremities thereof adapted to lie in substantially the same horizontal plane when said device is in operative clamping position whereby another can may be supported on said arm and member and remain in an upright position when so supported.

5. A device of the class described comprising a cover holding member having downwardly and inwardly extending claws at its opposite ends, a movable arm pivoted to said member substantially centrally of its length and having a downwardly and then inwardly extending claw on the free end thereof, and a cover engaging means on said arm so positioned with respect to said claws on said member and arm as to engage a cover to create a pressure to hold the same in place when said device is in operative position with said claws engaging retaining means on the can, the inner facing ends on said member being curved to substantially the same shape as the outer side walls of the can to which the same is to be applied, and the claw on said arm having the end thereof which engages the can cam-shaped to create a tension in said arm as the arm is pivoted into operative position, whereby said claws on said member and arm are drawn firmly into engagement with the sides of the can.

6. A device of the class described comprising a cover holding member having downwardly and inwardly extending claws at its opposite ends, a movable arm pivoted to said member substantially centrally of its length and having a downwardly and then inwardly extending claw on the free end thereof, and a cover engaging means on said arm so positioned with respect to said claws on said member and arm as to engage a cover to create a pressure to hold the same in place when said device is in operative position with said claws engaging retaining means on the can, the end of said claw on said arm which engages said can being cam-shaped to create a tension in said arm as said arm is pivoted into operative position, whereby said claws are all drawn firmly into engagement with the outside of said can.

50 7. A device of the class described comprising a cover holding member having downwardly and inwardly extending claws at its opposite ends, a movable arm pivoted to said member substantially centrally of its length and having a downwardly and then inwardly extending claw on the free end thereof, and a cover engaging means on said arm so positioned with respect to said claws on said member and arm as to engage a cover to create a pressure to hold the same in place when said device is in operative position with said claws engaging retaining means on the can, the cover engaging means on said arm having a detent portion adapted to cooperate with a detent portion on a cover to which said device is to be applied for preventing lateral shifting movement of said arm when said device is in operative position.

70 8. In a fastening device for holding a can cover in place, the combination with a member having at its opposite ends, downwardly and inwardly extending claws for engaging abutment surfaces on a can, an arm pivoted centrally of said member and extending substantially perpendicular thereto when in operative position, the move-

ment of said arm to one side of its operative position permitting said arm and member to be separated from said cover, said arm having at the free end thereof a downwardly and inwardly extending claw for engaging an abutment surface on the said cover and having a portion thereof intermediate its ends and engaging the cover for creating a clamping pressure when said fastening means is in operative position on a can, the same member and arm being provided with limiting means for preventing movement of said arm to one side of its operative position while permitting pivotal movement thereof in the opposite direction.

9. In a fastening device for holding a can cover in place, the combination with a member having at its opposite ends, downwardly and inwardly extending claws for engaging abutment surfaces on a can, an arm pivoted centrally of said member and extending substantially perpendicular thereto when in operative position, the movement of said arm to one side of its operative position permitting said arm and member to be separated from said cover, said arm having at the free end thereof a downwardly and inwardly extending claw for engaging an abutment surface on the said cover and having a portion thereof intermediate its ends and engaging the cover for creating a clamping pressure when said fastening means is in operative position on a can, said arm and member being provided with cooperating automatically operating detent means for holding said arm in operative position relative to said member against accidental displacement therefrom, but permitting relative movement thereof when manual pressure is applied thereto to release the clamping means.

10. In a fastening device for holding a can cover in place, the combination with a member having at its opposite ends, downwardly and inwardly extending claws for engaging abutment surfaces on a can, an arm pivoted centrally of said member and extending substantially perpendicular thereto when in operative position, the movement of said arm to one side of its operative position permitting said arm and member to be separated from said cover, said arm having at the free end thereof a downwardly and inwardly extending claw for engaging an abutment surface on the said cover and having a portion thereof intermediate its ends and engaging the cover for creating a clamping pressure when said fastening means is in operative position on a can, said arm and member having cooperating means for preventing pivotal movement of said arm relative to said member in one direction from their operative clamping position while permitting movement thereof in the opposite direction and said arm and member having detent means thereon to hold said member and arm in operative clamping position with each other against accidental displacement from that position.

11. In a fastening device for holding a can cover in place, the combination with a member having at its opposite ends, downwardly and inwardly extending claws for engaging abutment surfaces on a can, an arm pivoted centrally of said member and extending substantially perpendicular thereto when in operative position, the movement of said arm to one side of its operative position permitting said arm and member to be separated from said cover, said arm having at the free end thereof a downwardly and inwardly extending claw for engaging an abut-

- ment surface on the said cover and having a portion thereof intermediate its ends and engaging the cover for creating a clamping pressure when said fastening means is in operative position on a can, said arm and member being provided with cooperating detent means for holding said arm in operative position relative to said member against accidental displacement therefrom, that after a relatively small amount of movement of said arm relative to said member in its permitted direction of movement away from its operative position with respect to said member, the same will not retard the relative pivotal movement of said arm and member.
- 5 12. In a device of the class described, adapted to be used for closing the open mouth of a can, the combination with a cover for closing the mouth of said can and a fastening means comprising a pair of arms pivoted to each other, one 10 of said arms having downwardly and inwardly extending claws at the opposite ends thereof adapted to be arranged under a bead on the outside of the can to prevent upward movement of
- said arm, the other of said arms having at least one downwardly and then inwardly extending claw also adapted to engage said bead in a similar manner, said claws being so arranged peripherally of said can as to mutually cooperate to 5 prevent separation of said arms from said can by movement thereof in an upward direction, one of said arms having cover engaging means thereon for exerting a pressure on the cover centrally thereof to hold said cover in place on the can, 10 when said arms are in operative position beneath the bead on a can, said arms being relatively movable in a horizontal direction to permit said claws to be moved relative to each other in such a manner as to permit removal of said arms from 15 their operative positions, said end of said claw on said arm which engages said can being cam-shaped to create a tension in said arm as said arm is pivoted into operative position, whereby said claws are all drawn firmly into engagement 20 with the outer periphery of said can.

HENRY P. TURNER.
